UNITED STATES PATENT OFFICE

ROBERT S. CURLEY, OF LOWELL, MASSACHUSETTS, ASSIGNOR TO KITSON MACHINE SHOP, OF LOWELL, MASSACHUSETTS, A CORPORATION OF MASSACHUSETTS

COTTON-WORKING MACHINE

Application filed November 10, 1928. Serial No. 318,436.

This invention relates to machines for opening, picking or cleaning cotton and similar fibrous material herein included in the term "cotton." Such machines, hereinafter referred to as cotton cleaning machines, include a beater and a grid against which the cotton is thrown by the beater and through which a substantial part of the foreign material associated with the cotton is projected. In a typical cotton cleaning machine these grids are of angular cross section and they are usually supported at their opposite ends in cheek pieces carried by the frame of the machine. Usually, also, some means is associated with the cheek pieces to permit the angular adjustment of the grid bars and consequently to vary, as desired, the width of the spaces between adjacent bars. In some of these machines the bars are so long that their central portions are easily bent, and permanent bending and distortion of the bars is very likely to be produced by the bunching of the cotton at some point and the impact of the beater against it. The problem of supporting the intermediate portions of the grid bars is complicated by the fact that the presence of parts necessary to connect these portions of the bars in any way with the machine frame is highly objectionable, and by the further fact that the bars usually are mounted for angular adjustment, and any kind of a central support for bars so mounted must include some provision for permitting this adjustment.

The present invention aims to devise a thoroughly practical solution for this problem.

The nature of the invention will be readily understood from the following description when read in connection with the accompanying drawings, and the novel features will be particularly pointed out in the appended claims.

In the drawings,

Figure 1 is an angular view of a part of a cotton cleaning machine including a central support for the grid bars constructed in accordance with this invention;

Fig. 2 is a side elevation of the central sup-

port illustrated in Fig. 1 showing the grid bars in cross-section;

Fig. 3 is a view similar to Fig. 2 but showing the grid bars in different positions of adjustment;

Fig. 4 is a plan view of the support shown in Fig. 2;

Fig. 5 is a transverse sectional view of the support shown in Fig. 2;

Fig. 6 is a side view illustrating the mechanism for supporting the ends of the grid bars; and

Fig. 7 is a view partly in plan and partly in section showing the relationship of the center support to the end supports for the grid bars.

For purposes of illustration the invention is herein shown as applied to a cotton cleaning machine of a common commercial type. Referring to Figs. 1, 6 and 7 it will be observed that this machine includes a rotary beater having arms, one of which is shown in Fig. 1 at 2. These arms revolve close to a curved grid which comprises a series of parallel grid bars 3 of angular form in cross-section, these bars extending horizontally across the machine from one side thereof to the other. The opposite ends of the bars are supported in cheek pieces 4—4 which are bolted to the opposite sides of the machine frame, so the detailed construction of one of these cheek pieces being well shown in Fig. 6. Some of the bars have been omitted in this figure. It will be observed that the cheek pieces are provided with a series of sockets 5 in which the ends of the bars are located, and that the so-called "working edge" of each bar is constantly held in the upper right-hand corner of its respective socket, as shown in this figure, and against the capping strap 6 of the bar. The thinner edges of the bars rest in notches 7 formed in an adjusting member or dog 8 which is held to the cheek piece by a bolt 9. It is backed up by lugs 10—10 integral with the cheek piece and is provided with a slot 12 to receive the bolt 9 so that it can have a sliding adjustment of small amplitude. Such an adjustment rocks or swings the grid bars in unison about their working edges as pivots and thus changes

the width of the space between adjacent bars while maintaining the position of the working edges of the bars at a constant distance from the beater. By tightening the bolt 9 5 the dog 8 may be locked in its adjusted position where it clamps each of the grid bars against movement.

Usually the bars of each grid are divided into sections, each section containing a given 10 number, say six or eight bars, and two adjusting dogs, one at each end of the section, are provided for the bars of each section. This permits the adjustment of the bars of one section independently of those of another, 15 which often is very desirable. Fig. 6 shows the adjusting dog 8 for the upper section only of the bars of the grid, but Fig. 1 shows the adjusting dog 13 for the next adjacent section of bars. This supporting and adjusting 20 means for the bars has not been provided by this invention, but is here shown and described because of its bearing on the conditions with which the present invention deals.

As above stated, it would be highly objectionable to use any kind of a support for the central portions of the bars which would occupy any considerable space outside the bars. At the same time some support is extremely desirable when the bars are relatively long, say for example, thirty-six or 25 forty inches, or more. I have found that the requirements for an intermediate support can be satisfied by connecting the central portions of the bars rigidly together so that they 30 will support each other.

At the same time the bars will carry the supporting means. For this purpose I have provided an intermediate or center support 15, Figs. 1 to 5, inclusive, which comprises 35 a curved bar having a series of apertures 16 through which the grid bars 3 project. These apertures are of such shape that they permit the free angular adjustment of the bars and they are mounted in this support in much 40 the same manner that they are in the cheek pieces. That is, the working edge of each bar rests constantly in the upper right-hand corner of its respective aperture 16, and it is held in this position by an adjusting member 45 or dog similar to the adjusting dogs 8 and 13. In the construction shown in Figs. 2 and 3 two of these dogs 17 and 18 are provided, each adapted to accommodate eight of the bars 3 and each having notches to receive the 50 thin edges of the bars. These dogs slide on lugs 19 integral with the bar and they may be clamped in their adjusted positions by tightening up the bolts 20 and 21, respectively.

60 In order to prevent these parts from loading up with lint, the bar 15 is provided with a web or flange 22 which lies immediately in front of the grid bars and is of such dimensions as to protect the parts immediately 65 behind it. In other words, this part 22 forms

a guard to shield the adjusting dogs and adjacent parts from lint and other material thrown through the grid by the beater. It will be seen from an inspection of Figs. 4 and 5 that the guard is made of greater width at 70 that side of the bar 15 on which the adjusting dogs are mounted.

In adjusting the bars initially the bolts 20 and 21 are loosened and the bars are then adjusted at the cheek pieces exactly as 75 they are when the machine is not provided with the center support. When this adjustment has been completed and the adjusting members have been tightened up, then the bolts 20 and 21 are tightened. It will be clear 80 from an inspection of Figs. 2 and 3 that when this has been done the central portions of the bars then are all connected rigidly to each other through the supporting bar 15 and the adjustable dogs. While the grid bars themselves form the sole support for the bar 15, nevertheless the shape of this bar is such that it is very strong and rigid, and when the grid bars are connected to it in the manner just described the entire assembly forms a very rigid 85 structure and substantially eliminates any possibility of the individual grid bars being bent or deformed in the manner above described. The fact that the grid bars and supporting bar 15 cooperate in this manner and 90 make any external support unnecessary is an important practical advantage in avoiding the presence of obstructions in the space outside the beater through which the dirt and foreign materials are discharged. If the 95 adjustment of the grid bars is eliminated, the construction of the center support can be correspondingly simplified.

While I have herein shown and described a preferred embodiment of my invention it will 100 be understood that the invention may be embodied in other forms without departing from the spirit or scope thereof.

Having thus described my invention, what 110 I desire to claim as new is:

1. In a cotton cleaning machine having a beater, a grid positioned closely adjacent to said beater and comprising a series of bars, means for supporting the ends of said bars, and additional means for supporting said 115 bars at points between their ends and connecting them rigidly together so that they cooperate to support each other, said additional means being supported solely by said bars.

2. In a cotton cleaning machine having a beater, a grid positioned closely adjacent to said beater and comprising a series of bars, means for supporting the ends of said bars for angular adjustment, and additional 120 means for engaging said bars between their ends and connecting them rigidly together whereby they cooperate to support each other, said additional means serving to support 125 said bars in their various positions of angular 130

adjustment but being itself supported solely by said bars.

3. In a cotton cleaning machine having a beater, a grid positioned closely adjacent to said beater and comprising a series of bars, means for supporting the ends of said bars, and means supported independently of said end supporting means for engaging the intermediate portions of said bars and connecting them rigidly together and thereby causing them to support each other.

4. In a cotton cleaning machine having a beater, a grid positioned closely adjacent to said beater and comprising a series of bars, means for supporting the ends of said bars for angular adjustment, additional means supported independently of said end supporting means for engaging said bars between their ends and supporting them, and adjustable means for engaging said bars and cooperating with said central supporting means to hold the bars in their adjusted positions.

5. In a cotton cleaning machine having a beater, a grid positioned closely adjacent to said beater and comprising a series of parallel bars of angular cross section, means for supporting said bars at their opposite ends, a supporting bar having apertures through which said grid bars extend and in which intermediate portions of the bars are supported, said supporting bar being itself supported solely by said parallel bars, an adjustable member slidably mounted on said supporting bar and having shoulders to engage said grid bars, and means for clamping said member in its adjusted position.

6. In a cotton cleaning machine having a beater, a grid positioned closely adjacent to said beater and comprising a series of parallel bars of angular cross section, means for supporting said bars at their opposite ends, a curved bar having apertures through which said grid bars extend and in which intermediate portions of the bars are supported and having a web portion forming a guard lying in front of said grid bars and extending at right angles to them, said supporting bar being itself supported solely by said parallel bars, a dog slidably mounted on said curved bar and cooperating with said grid bars to hold them in various positions of angular adjustment, and means for locking said dog to said curved bar.

55 ROBERT S. CURLEY.
